UNITED STATES PATENT OFFICE.

EDWARD W. CLARKE, OF WILMINGTON, DELAWARE.

APPARATUS FOR MOLDING LINK CHAINS.

1,228,534.

Specification of Letters Patent.

Patented June 5, 1917.

Application filed May 6, 1916. Serial No. 95,881.

To all whom it may concern:

Be it known that I, EDWARD W. CLARKE, a citizen of the United States, residing at Wilmington, in the county of New Castle and 5 State of Delaware, have invented certain new and useful Improvements in Apparatus for Molding Link Chains, of which the following is a specification, reference being had to the accompanying drawings.

10 This invention relates to an improved apparatus for molding link chains and has for its primary object to provide means whereby anchor chains and the like, which are required to sustain severe strains, may be cast 15 and molded with one-piece, jointless links.

It is a more particular object of the invention to provide a sand mold flask constructed in quarter sections, and improved means for assembling the flask sections so 20 that the corresponding link impressions in the mold sand are disposed in mating relation to form the complete links of the chain upon the casting of the metal.

It is another object of the invention to 25 provide an apparatus for the molding of jointless chain links, embodying a stripping plate, means for arranging patterns of sectional parts of a series of connected links upon the stripping plate, and a mold flask 30 adapted to be arranged upon the stripping plate to receive the mold sand, said patterns being disposed in planes alternately at right angles to each other and each mounted upon an individual stool plate whereby they may 35 be removed from the stripping plate without breaking up the mold sand.

It is a further general object of the invention to provide a very simple apparatus for the molding of chain links whereby the 40 same may be inexpensively produced and the highest possible strength obtained in the formation of the links.

With the above and other objects in view, my invention consists in the novel features 45 of construction, combination and arrangement of parts to be hereinafter more fully described, claimed and illustrated in the accompanying drawing, in which,

Figure 1 is an elevation of the stripping 50 plate with the link patterns arranged thereon;

Fig. 2 is a top plan view showing the flask arranged upon the stripping plate to receive the mold sand;

55 Fig. 3 is a transverse section taken on the line 3-3 of Fig. 2;

Fig. 4 is a face view of the flask and the mold removed from the stripping plate;

Fig. 5 is a side elevation showing the sections of the mold flask assembled; and

60

Fig. 6 is an end elevation thereof.

Referring in detail to the drawing, 5 designates the base of the stripping plate and 6 the vertical wall thereof rising from one longitudinal edge of the base wall 5. The 65 walls 5 and 6 of the stripping plate are provided with slots therein defining one-half of a series of connected links, as indicated at 7 and 8 respectively. It will be observed that I have shown in the accompanying 70 drawing, a link of the common stud type, wherein the same is provided with a central transverse connecting bar or stud. Links of this form are generally used in anchor chains or in the construction of other chains 75 which are designed to sustain severe strains.

9 designates the stool plates, each of which has one-half of a chain link 10 formed upon one face thereof. These link patterns are of sufficient width to extend through the slots 7 80 and 8 cut in the walls of the stripping plate and to project from the opposed faces of said angularly disposed walls for a distance equivalent to one-half of the cross-sectional diameter of the link to be formed. As seen 85 in Fig. 2 of the drawing, the patterns are inserted through the walls of the stripping plate at the bottom and rear faces thereof respectively, the stool plates 9 limiting the movement of the patterns through the openings in the plate and lying closely against the faces of the stripping plate. In each end of the base wall 5 of the stripping plate, a vertical opening 11 is formed, and a similar opening 12 is also provided in each end of 90 the vertical wall 6 of the stripping plate.

The mold flask is constructed in four sections. As each section of the flask is identical in construction with every other section thereof, the detail description of one 100 will suffice for all. Each flask section includes a longitudinally extending body wall 13 having end walls 14 at its extremities projecting at right angles to the body wall and in the same direction therefrom. Between the end walls 14, a plurality of equidistantly spaced webs or partitions 15 are formed upon the body wall 13. The lower edges of these partition or division walls are obliquely inclined upwardly from the lower edge of the body wall 13 to a point in spaced 105 relation to the plane of the upper edge of

said wall, as indicated at 15'. The free vertical edges 16 of these partitions are disposed out of alinement of the vertical edges of the end walls 14 longitudinally of the 5 mold section or, in other words, said partitions have a maximum width above the inclined edges 15' thereof which is appreciably less than the width of the end walls 14 of the flask section. Laterally projecting, apertured ears 17 are formed upon each end 10 wall 14 at its lower edge, and a similar apertured ear 18 is also formed upon the vertical edge of each end wall.

After the patterns 10 have been arranged 15 in the walls of the stripping plate in the manner above stated, a flask section is arranged upon the base 5 of the plate with the edges of its end walls 14 in contact against the face of the vertical wall 6. Pins 20 indicated at 19 are inserted through the ears 17 and 18 and the coinciding openings 11 and 12 respectively, in the walls of the stripping plate, whereby the flask section is held in position. The mold sand is now 25 tightly packed into the flask around and upon the pattern link sections 10 and between the division or partition walls 15. A suitable handle 20 is fixed to each of the end walls 14 of the flask section whereby it may 30 be readily removed from the stripping plate after the sand has been properly rammed in the flask and the patterns withdrawn through the stripping plate. It will be understood that, prior to the removal of the 35 flask section from the stripping plate, the stool plates 9 carrying the patterns 10 mounted in the vertical wall 6 of the stripping plate, are withdrawn or removed by moving the stool plates away from the face 40 of said wall outwardly in a direct horizontal line. The flask and mold may then be readily lifted from the base wall 5 of the stripping plate. The patterns 10, of course, produce the metal receiving channels in the 45 adjacent angularly disposed walls of the mold which conform in every particular to the shape or configuration of the link pattern sections. The sand is also rammed or packed tightly in the spaces between the vertical edges 16 of the division or partition 50 walls 15 and the face of the vertical wall 6 of the stripping plate so that when the flask sections are assembled, the metal division walls 15 will not contact at their free 55 edges which would prevent the proper assemblage of the flask sections particularly if the same are slightly warped.

After each section of the mold has been 60 formed in the manner above stated, the flask and mold sections are assembled in the manner shown in Figs. 5 and 6 of the drawing, the metal receiving grooves or channels in the mold defining corresponding link sections being arranged in opposed mating 65 relation. When these quarter sections of the

mold are assembled, the apertured ears 17 and 18 of the adjacent sections are disposed upon each other and receive the fastening pins indicated at 21. Pouring openings are formed by cutting grooves or channels 22 70 in the face of one pair of sand molds communicating with the alternate links which are disposed in a vertical plane at the upper sides thereof.

The lower pair of sand molds are first 75 assembled and locked together by means of the pins 21, and then metal links which have been previously cast are horizontally disposed in the channels formed in the upper faces of said mold sections. The two upper 80 mold sections are then arranged in place, said cast links being received in the channels in the lower faces of the latter molds while the metal receiving channels for the vertically disposed links coinciding with the corresponding channels in the lower pair of 85 mold sections, complete the mold to receive the molten metal. The metal is then poured through the openings provided by the grooves or channels 22 in the mold sections 90 to fill the vertically disposed mating channels defining the vertical links, and thus produce a continuous metal link body without seam or joint connected to the adjacent horizontally disposed cast links. It is apparent, of course, that the molds may be 95 made of any desired length so that a greater or less number of links may be cast in each operation.

From the foregoing description, taken in 100 connection with the accompanying drawing, the construction, manner of operation and several advantages of my improved casting apparatus for the manufacture of link chains will be fully and clearly understood. 105 By first forming the molds in a number of sections, the same may be easily and quickly assembled and the patterns can be easily removed after the packing or tamping of the mold, without liability of breaking up the 110 sand, so that a perfect product will result. As above stated, the prime essential in the manufacture of anchor chains or other chains which must sustain excessive strains, is that the links must have a maximum of 115 tensile strength, and it is, therefore, desirable that all joints or seams in the links should be eliminated. By means of my improved apparatus, this purpose is fully attained. It is manifest, of course, that if desired, the present invention may also be employed for the casting of the ordinary type 120 of chain link without the central stud.

While I have shown and described the preferred construction and arrangement of the 125 several features of my invention, it is to be understood that the same is susceptible of considerable modification therein and I, therefore, reserve the privilege of adopting all such legitimate changes as may be fairly 130

embodied within the spirit and scope of the invention as claimed.

Having thus fully described my invention, what I desire to claim and secure by Letters 5 Patent is:—

1. An apparatus for forming link chain molds in quarter sections including a stripping plate having walls extending at right angles to each other, each of said walls being 10 provided with means to removably receive a plurality of link patterns, a flask section having a body wall adapted to be arranged on edge on one wall of the stripping plate and in spaced, parallel relation to the other wall 15 thereof, said flask section having angular end walls contacting with the face of the latter wall of the stripping plate, and means for detachably securing said end walls of the 20 flask section to the walls of the stripping plate.
2. An apparatus for forming link chain molds in quarter sections including a stripping plate having walls extending at right angles to each other, each of said walls being 25 provided with means to removably receive a plurality of link patterns, a flask section having a body wall adapted to be arranged on edge on one wall of the stripping plate and in spaced, parallel relation to the other wall 30 thereof, said flask section having angular end walls contacting with the face of the latter wall of the stripping plate, a plurality of spaced webs integrally formed with the body wall of the flask section and extending at 35 right angles thereto, said webs being of less width than the end walls and having their end edges spaced from the face of the first named wall of the stripping plate, and means for detachably securing the end walls of the 40 flask section to the stripping plate.

In testimony whereof I hereunto affix my signature in the presence of two witnesses.

EDWARD W. CLARKE.
